UNITED STATES PATENT OFFICE.

JOSEPH ANTHONY SCHLEHR, OF CHICAGO, ILLINOIS.

WASHING-MACHINE.

1,255,343.

Specification of Letters Patent.

Patented Feb. 5, 1918.

Application filed October 30, 1916. Serial No. 128,537.

To all whom it may concern:

Be it known that I, JOSEPH A. SCHLEHR, a citizen of the United States, residing at Chicago, in the county of Cook and State 5 of Illinois, have invented certain new and useful Improvements in Washing-Machines; and I do declare the following to be a full, clear, and exact description of the invention, such as will enable others skilled in the art 10 to which it appertains to make and use the same.

This invention relates to improvements in washing machines of the pounder type.

The main object of the invention is to 15 provide a machine of this character the pounder of which is so constructed as to force the water through the clothes into the pounder and to eject it therefrom in the form of a spray.

20 Another object is to so construct and mount the pounder operating lever that the pounder may be positioned in any part of the tub during the operation of the machine.

25 Another object is to so mount the pounder actuating lever that proper leverage may be obtained for manipulating the pounder and yet sufficient strength be afforded to withstand all strains to which it may be subjected.

30 With these and other objects in view the invention consists of certain novel features of construction, and the combination and arrangement of parts as will be more fully 35 described and claimed.

In the accompanying drawings:

Figure 1 is a vertical section of a tub with this improved machine applied and shown partly in side elevation and partly in section;

40 Fig. 2 is a vertical section taken through the connection of the pounder with the operating lever, the remainder of the pounder being shown in side elevation.

45 In the embodiment illustrated, the machine or apparatus constituting this invention is shown applied to an ordinary wash tub T and comprises a tub engaging member in the form of an upright or standard 1 having its lower end bifurcated and the furcations 2 thereof straddling the edge of the tub and removably clamped thereto by thumb screws 3. This standard 1 projects any suitable or desired distance above the 50 upper edge of the tub and has a pintle 4 projecting upwardly therefrom on which an

arm 5 is mounted to swing in a horizontal plane.

The arm 5 is curved longitudinally upward with a bearing 6 at one end pivotally 60 engaged with the pintle 4 and having a pintle 7 projecting upwardly from its free end. By so curving and mounting this arm 5 its free pintle carrying end will be positioned some distance above the upper edge of the 65 tub and will extend laterally thereover, its pivotal connection with the standard 1 adapting it to be swung to any desired point over the tub.

A pounder or plunger actuating lever 8 is 70 mounted on the arm 5 having a hinged connection therewith which permits it to swing laterally and vertically. The connection or hinge for this lever 8 comprises a bearing 9 adapted to be engaged with the pintle 7 to 75 swing in a horizontal plane and is provided with laterally extending laterally spaced apertured ears 10 between which one end of the lever 8 is mounted and pivotally connected therewith to swing in a vertical 80 plane. This lever 8 is composed of metal and is provided at its outer end with a socket 11 in which is mounted a wooden handle 12 although obviously it may be made as a unitary structure if found desirable. The lever 85 8 is provided intermediately of its ends with a boss 13 having a bore extending vertically therethrough with the side walls thereof flared at its opposite ends as shown at 14 and 15 for a purpose to be described. A 90 coiled spring 16 is secured at one end to the boss 13 and at its other end to the arm 5 and exerts its tension to normally hold the lever in lowered position and to return it to such position after it has been raised. This 95 spring also operates to return lever 8 to normal position after it has been turned laterally on pivot 7.

Carried by the lever 8 is a pounder constructed in the form of a hollow bell-shaped 100 member 17 having its lower end closed by a foraminous plate 18 and with the side walls thereof provided adjacent its lower edge with a series of apertures 19 preferably arranged in peripheral alinement 105 and which are designed to act as a spray as will be presently described. The upper end of the bell-shaped member 17 which is composed of any suitable sheet metal has a horizontally disposed reinforcing partition 20 110 through which extends a shank receiving socket 21 which is shown with its lower edge

upset against the inner face of said partition whereby said socket is securely connected thereto. This socket 21 projects above the upper end of the bell-shaped member 17 and has secured therein a shank or handle 22 which is provided with a plurality of longitudinally spaced apertures 23 which extend transversely therethrough and are designed for adjustably connecting the 10 pounder with the lever 8 as will now be described. This shank or handle 22 is inserted in the bore of the boss 13 of said lever and is pivotally connected therewith by means of a thumb screw 24 which extends transversely 15 through the bore between the flared ends thereof and is designed to pass through one of the apertures 23 in the shank 22 and thereby pivotally connect said shank with the lever, the flared ends of which permit a 20 rocking movement of the shank in order that the latter may be retained in a vertical position regardless of the position or inclination of the actuating lever. The provision of the apertures 23 in the shank 22 25 provides for the adjustable connection of said shank with the lever.

From the above description it will be 30 obvious that by providing the two pivoted connections at 4 and 7 the pounder may be readily operated in any portion of the tub as the actuating lever 8 has a wide range of lateral and vertical movement so that the pounder may be carried toward or from the center of the tub as desired.

35 The construction of the bell-shaped member 17 of the pounder with the perforated bottom causes the water in the tub, when said pounder is brought into forcible engagement with the clothes contained therein, to pass through the clothes up into the bell-shaped member 17 and to be discharged 40 through the peripheral openings 19 in the

form of a spray which greatly facilitates the cleansing operation, it being understood that when the water is forced up into the 45 member 17 the air therein is compressed and operates to force the water out through the apertures 19 in the lower end of the member 17.

It will thus be understood that in the 50 operation of this machine the handle 12 is grasped by the operator and reciprocated vertically whereby the pounder on its down stroke is brought into forcible engagement with the clothes contained in the tub and 55 the water will be forced up into the member 17 and out through the apertures 19 in the manner above described. The operator may, as stated above, position the pounder at any desired point within the tub so that all the 60 clothes contained therein will be subjected to the washing operation.

I claim as my invention:

A clothes washing machine comprising a tub, a horizontally swinging arm mounted 65 on said tub and directed laterally and upwardly, a bearing mounted on the free end of said arm for horizontal turning, a lever fulcrumed at its front end to said bearing for vertical swinging, a clothes pounder having a vertical staff pivoted to said lever, and a coiled spring connected at one end to said lever adjacent the pivotal connection of said staff, the other end of said spring being anchored to said arm in substantially vertical alignment with said bearing, but below 70 the same.

In testimony whereof I have hereunto set my hand in the presence of two subscribing witnesses.

JOSEPH ANTHONY SCHLEHR.
